1 Claim

ABSTRACT OF THE DISCLOSURE

A well tool for determining the presence and position of a plug established by plug forming material in a well bore, generally prior to hardening of the plug forming material, which tool comprises a shoe plate means adapted to be removably secured to the lower end of a pipe string and including a relatively large diameter disk-like plate normal to the longitudinal axis of the pipe string and wherein the plate is freely slideable within the well bore but has a radial cross-sectional area greatly in excess of the radial cross-sectional area of the pipe string whereby the effective force exerted per unit area of lower surface of the pipe string can be substantially reduced to permit the pipe string with the tagging shoe attached thereto to be supported by plugging material within the bore of a well whereby the presence of a downhole plug may be determined from the well head prior to setting of an initially fluent plugging material.

The present invention relates to a well plug tagging method and means. More particularly, the present invention relates to the provision of a well plug tagging shoe to be utilized in a well cementing procedure to determine the presence of a well bore plug formed by a generally cementitious material introduced into a well bore. More specifically, the present invention relates to a well plug tagging shoe which may be removably coupled to the lowermost connector of a pipe string.

In the setting of cementitious well bore-occluding plugs in wells drilled, primarily for gas and oil, but not necessarily excluding water, it frequently is necessary to prove the existence or effectiveness of such plugs by "tagging" them. The usual practice has been to cement the plug i.e., introduce the cementitious material into the bore hole, with a string of pipe that is open-ended. In such a case the cross-sectional area bearing upon the cementitious material is small, being the cross-sectional area of the pipe, and the cementitious material must be allowed to harden to a great degree before it is sufficiently competent to bear the static weight of the pipe string without permitting the string to pass downwardly therein which occurrence is highly undesirable inasmuch as it adversely effects the plug being established and also does not permit the accurate determination of the existence and position of the cementitious plug.

Accordingly, it is a primary object of the present invention to provide a well tool, i.e., tagging shoe, for rapidly and accurately determining the presence and position of a well plug established by plug-forming material in a well bore generally prior to final hardening of the plug-forming material.

Another object of the present invention is to provide a novel method of rapidly and accurately determining the presence and position of a well plug established by plug-forming material introduced into a well bore wherein removably secured shoe plate means is provided for substantially increasing the contact area of the lowermost end portion of a pipe string whereby generally cementitious plug-forming material within the well bore can be

2

"tagged" at a much earlier stage in the process of its setting or hardening whereby significant economies of operation will be realized due to a reduction in the time required to satisfactorily complete the plugging of wells drilled for gas, oil and water.

Still another object of the present invention is to provide a novel construction for a well plug tagging shoe having a generally tubular body portion provided with coupling means to be removably secured to the lowermost pin or box connector portion of a drill pipe string or the like and wherein the body portion is provided with a generally disk-like shoe plate of substantially greater radial cross-sectional area than the lower end of the pipe string and wherein the major axis of the shoe plate is generally normal to the longitudinal axis of the pipe string to which the tagging shoe is secured.

Still a further object of the present invention is to provide a well plug tagging shoe of the aforementioned general construction wherein the tubular body portion and/or the shoe plate are provided with a plurality of circulation or relief ports to permit the circulation of fluid during utilization of the tool, if desired, and to generally preclude floating of the tagging shoe on relatively non-viscous fluid within a well bore above a portion of generally cementitious or plastic plugging material within the well bore to be tagged by the tool.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a longitudinal cross-sectional view through a plugged well bore further showing an exemplary embodiment of a tagging shoe constructed in accordance with the present invention and removably secured to the lowermost section of a pipe string as utilized in the method of the present invention;

FIGURE 2 is an enlarged longitudinal cross-sectional view of the exemplary tagging shoe of FIGURE 1 taken substantially along the plane of the line 2—2 of FIGURE 1 and showing circulation or relief port details thereof;

FIGURE 3 is a transverse, or radial, cross-sectional view taken substantially along the plane of the line 3—3 of FIGURE 2; and

FIGURE 4 is a perspective view of the exemplary tagging shoe of the preceding figures.

Briefly, the method of the present invention for the rapid, accurate determination of the presence and position of a generally cementitious well plug forming body of material within a well bore utilizes a well plug tagging shoe provided with a load bearing surface substantially larger in area than normally provided by the lowermost portion of a pipe string whereby a shoe plate provided on the lower end of the well tagging shoe, and having its major axis generally normal to the longitudinal axis of the pipe string and thus also the well bore, reduces the effective static weight of the pipe string by substantially reducing the effective weight per unit area of the string whereby the material utilized to establish the plug may be tested for the presence and position thereof by the tagging shoe before the material has substantially hardened.

Referring now in greater detail to the drawings, and FIGURE 4 in particular, it will be seen that the exemplary embodiment 10 of a well plug tagging shoe constructed in accordance with the invention includes a generally tubular tool body portion 14 having a fluid passage defining bore 16 extending longitudinally therein. The upper portion of the tool body 14 is provided with a coupling means 18, which in the embodiment illus-

trated, comprises the threaded box portion of a threaded pin and box connector means conventionally utilized in well apparatuses. In this regard, and as best seen in FIGURE 2, the well plug tagging shoe 10 is illustrated as operatively positioned on the lower end portion of a pipe string section 20 having a threaded pin coupling means 22 complementary to the threaded box 18 whereby the tagging shoe 10 can be removably secured to the pipe string section 20 with the fluid passage defining bore 16 in communication with a fluid circulating bore 24 as conventionally provided in well pipe strings.

A shoe plate means 26 is fixedly secured to or otherwise rigidly affixed to the lower end portion of the tool body 14, which securing in the embodiment illustrated comprises an annular well bead indicated generally 28 and a bracing means comprising a plurality of bracing gussets 30 secured to both the body portion 14 and the shoe plate 32 so as to further rigidify the securing of the tagging shoe means 26 to the body portion 14. The bracing gussets 30 may be secured in the relationship illustrated by welding. It will be understood that the manner in which the shoe plate 32 is secured to the body portion 14 is merely exemplary and does not preclude, for example, securing the shoe plate 32 to the body portion 14 by other suitable means such as fasteners, a threaded coupling, as long as the securing is relatively rigid. Furthermore, it will also be understood that the threaded box connector portion 18 is merely exemplary of a plurality of conventional connector means which can be utilized in securing the well plug tagging shoe 10 to the lower end of a pipe string or the like. Still further, it will be appreciated that the length of the body portion 14 illustrated is merely exemplary.

The well plug tagging shoe 10 may further include a fluid circulation port means comprising one or more through apertures in the body portion 14 and/or the shoe plate 32 which through apertures place the bore 16 in direct communication with the exterior of the body portion 14, and thus the well annulus thereabout above the shoe plate 32 and/or alternatively place the bore 16 in direct communication with the underside of the shoe plate 32. Circulation ports as discussed hereinabove are indicated generally at 34 and 36 respectively. In addition, the tagging shoe plate 32 may be provided with one or more through apertures as indicated at 38 which place the upper and lower surfaces of the tagging shoe 32 in direct communication to permit circulation of relatively non-viscous fluid as indicated at 40 within the annulus defined by the bore wall 42, or alternatively a casing, not shown, so as to generally permit unimpeded movement of the well plug tagging shoe 10 downwardly and upwardly within the fluid 40 containing bore. It will be understood, of course, that when providing the tagging shoe plate 32 with circulation ports as at 36 and 38 that the amount of material removed by such ports will in part be limited by the total bearing surface area of the underside of the tagging shoe plate 32 which is required to support the complete or partial weight of the pipe string to which the tool 10 is operatively secured.

With further regard to the tagging shoe plate 32, and inasmuch as the shoe is adapted to substantially reduce the force exerted by the pipe string per unit of surface area, the tagging shoe plate 32, which is of a generally disk-like configuration, is normally devised so as to have a great radius as is possible, which radius is always substantially larger than the radius of the lower end of the pipe string, but of somewhat smaller radius than that of the bore hole or casing within which the tool 10 is utilized. Furthermore, it will be appreciated that the circular disk-like configuration of the shoe plate 32 illustrated is merely exemplary in that the plate 32 could be of numerous configurations, i.e., convex, concave, wedge-shaped and need not necessarily have circulation ports therein or alternatively the shoe plate 32 may be provided with a back pressure valve, such as in the aperture

36, so that fluid could pass downwardly through the valve yet no fluid could pass upwardly through this valve as the tool is lowered into the hole.

With further regard to the bracing gussets 30, they serve as combination brace and tool guide means inasmuch as very often the tagging shoe 10 will be run through well casing adjacent the ground surface to tag a plug in a portion of the bore hole which has been drilled to a depth below that of the lower end of the well casing. Therefore, when utilizing the tagging shoe 10 under such conditions, as the tagging shoe 10 is withdrawn from the bore hole, there is the possibility of it "hanging up" on the bottom of the casing. In fact, other bore hole obstructions can be encountered, i.e., side-tracked pieces of pipe, metal objects that occasionally fall into the bore hole and are subsequently drilled past but continue to protrude into the bore hole, pieces of formation rock that heave out into the bore hole, etc. It will therefore be appreciated that the gussets 30, which generally extend from the upper peripheral edge of the shoe plate 32 to the outer surface of the body member 14, are generally of such configuration that they provide a sloping cam surface to facilitate guiding the tagging shoe 10 past or through obstructions such as mentioned hereinabove. In addition it will be appreciated that by rotation of a tool string to which the tagging shoe 10 is removably secured, many of such obstructions could be gradually broken up and subsequently washed away.

Referring now to the utilization of the well plug tagging shoe 10 and the instant method of accurately determining the presence and position of a plug within a well by utilization of the tool 10, it will be seen in FIGURES 1 and 2 that the tool 10 has been affixed to the lowermost section of pipe 20 which comprises a portion of a pipe string extending to the well head. In FIGURE 1 it will further be seen that the lower portion of the bore 42 has been filled with a generally settable plug forming material 44 such as comprising a cementitious composition or alternatively a resinous composition and for that matter any solid, semi-solid or extremely viscous material that has been placed in a bore hole or casing and whose presence it is desired to verify by resting any or all of the weight of a pipe string upon it. For purposes of discussion herein the plug material 44 is illustrated as being a settable cementitious composition and in FIGURES 1 and 2 it will be understood that it is desired to rapidly determine the presence and position of the upper surface 46 of a plug formed thereby and accordingly it will be understood that in FIGURES 1 and 2 the plug material 44 has at best only attained a very initial set of relatively low load bearing strength. Were it not for the relatively great total surface bearing area of the plate 32 the determination of the presence and position of the upper surface 46 of the plug material 44 could not generally be determined inasmuch as a pipe string not provided with the device 10 would sink downwardly within the relatively unconsolidated plug material 44 to such an extent that the presence of the plug material 44 could not be verified or alternatively a substantial amount of time would have to be lost in permitting the plug material 44 to set to its final rigidity to enable verifying the presence of the plug with a pipe string not provided with the tool 10.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A method of determining the presence and position of an unconsolidated plug established by a settable cemen-

titious plug-forming material in a generally restricted diameter bore hole of a well prior to significant consolidation of the settable plug-forming material, wherein the bore hole is filled with at least a two phase column of liquid comprising at least an upper relatively non-viscous circulating liquid phase and a lower relatively viscous phase comprising the settable plug-forming material, which method comprises the steps of making up and lowering into the well a pipe string having means on the lower end thereof of a diameter lesser than the diameter of the bore hole and capable of supporting the weight of the pipe string on the unconsolidated plug while maintaining circulation of the relatively non-viscous phase of the liquid column in the bore hole, and verifying the presence of and position of the unconsolidated plug by cessation of downward movement of the pipe string.
